UNITED STATES PATENT OFFICE

CARL ARNOLD, OF NUEREMBERG, GERMANY

RACK-OPERATED TOY

Application filed November 19, 1929, Serial No. 408,307, and in Germany October 28, 1929.

This invention relates to a rack operated toy locomotive the wheels of which are rapidly rotated by a driving wheel adapted to be operated by a rack, sparks being produced at the same time by a spark producing device and ejected through the smoke stack so that they become visible.

An embodiment of the invention is illustrated by way of example in the accompanying drawing in which

Fig. 1 is a front elevation and

Fig. 2 a rear elevation of the toy locomotive.

The toy according to the invention consists of a rack operated driving mechanism *a* of known type, which has auxiliary gear wheels *b* and *c*. On the front side of the driving mechanism *a* a plate *f* of sheet metal or other suitable material imitating a locomotive is fixed and painted accordingly. On this plate *f* two wheels *g* and *i* are rotatably mounted, the wheel *g* being rotated directly by the shaft *h* of the driving mechanism *a* and the wheel *i* by a connecting rod *k* from the wheel *g*. The axle of the locomotive wheel *i* is journaled in a reinforcing piece *l* on the rear side of the plate *f* imitating a locomotive. On the locomotive wheel *g* a second connecting rod *k* is mounted which operates a piston rod engaging with a piston.

On the driving mechanism *a* a friction disc *m* is further arranged and rotated by said driving mechanism. A cerium stone *p* in the end of an oscillatable lever *o* bears against said friction disc. The sparks produced by the friction of the cerium stone on the friction disc are projected through a smoke stack *q* fixed on plate *f* so that they are visible from the outer side.

For the rack drive a screw spindle drive may be substituted.

I claim:

1. A rack operated toy, comprising in combination a rack operated driving mechanism of known type, a plate fixed on the front side of said driving mechanism said plate shaped and painted to represent a locomotive, a large wheel rotatably mounted on the front side of said plate on the end of the shaft of said driving mechanism, a connecting rod hingedly mounted on said wheel and a second locomotive wheel journaled on said plate and rotated by said connecting rod.

2. A rack operated toy, comprising in combination a rack operated driving mechanism of known type, a plate fixed on the front side of said driving mechanism said plate shaped and painted to represent a locomotive, a large wheel rotatably mounted on the front side of said plate on the end of the shaft of said driving mechanism, a connecting rod hingedly mounted on said wheel, a reinforcing piece on the rear side of said plate, a second locomotive wheel journaled on said reinforcing piece and rotated by said connecting rod, a second connecting rod on said wheel, and a piston rod hingedly fixed on the outer end of said second connecting rod.

3. A rack operated toy, comprising in combination a rack operated driving mechanism of known type, a plate fixed on the front side of said driving mechanism said plate shaped and painted to represent a locomotive, a large wheel rotatably mounted on the front side of said plate on the end of the shaft of said driving mechanism, a connecting rod hingedly mounted on said wheel, a reinforcing piece on the rear side of said plate, a second locomotive wheel journaled in said reinforcing piece and rotated by said connecting rod, a second connecting rod on said wheel, a piston rod hingedly fixed on the outer end of said second connecting rod, a casing representing a smoke stack fixed on the rear side of said plate, and a spark producing device of known type driven from said driving mechanism arranged under said casing so that the sparks produced are thrown out through said casing.

In testimony whereof I affix my signature.

CARL ARNOLD.
